The ornamental design for a cover for mobile phone, as shown and described.

DESCRIPTION

FIG. 1 is a front perspective view of a cover for mobile phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is an enlarged view of the encircled portion as shown in FIG. 5.

In FIGS. 5 and 9, the dot-dash broken lines encircle and indicate a portion of the claimed design shown on an enlarged scale in FIG. 9. All other dot-dash broken lines represent boundaries of the claimed design. The dash-dash broken lines depict unclaimed environmental features of the cover for mobile phone and form no part of the claimed design.
